PIETRO CINQUINI, OF WEST MERIDEN, CONNECTICUT, ASSIGNOR TO BRADLEY & HUBBARD, OF SAME PLACE.

Design No. 4,984, dated June 13, 1871.

DESIGN FOR A CHANDELIER.

The Schedule referred to in these Letters Patent and making part of the same.

To all whom it may concern:

Be it known that I, PIETRO CINQUINI, of West Meriden, in the county of New Haven and State of Connecticut, have invented a new Design for Chandelier; and I do hereby declare the following, when taken in connection with the accompanying illustration, to be a full, clear, and exact description of the same, and which said illustration constitutes part of this specification, and represents a front view.

This invention relates to a design for chandeliers for gas-burners or supporting-lamps, particularly to that class known as single-light chandeliers, and consists in the peculiar configuration of the chandelier, as fully shown in the accompanying photographic illustration.

From a center two arms or rods extend down, each supporting one end of the cross-bar at the bottom.

The cross-bar is the particular feature of the design, and its configuration is fully and clearly shown in the accompanying illustration.

The suspending-rods are, by preference, ornamented, and the center, at the top, is also made ornamental; but by my design I wish to be understood as claiming the peculiar configuration of the cross-bar, with or without the ornamentation of the suspending-rods in the center.

I claim as my invention—

The design for chandeliers, as hereinbefore described and shown in the accompanying illustration.

PIETRO CINQUINI.
